UNITED STATES PATENT OFFICE.

WILLIAM CROSSLEY, OF NEW HAVEN, CONNECTICUT.

FACTORY-CAR.

SPECIFICATION forming part of Letters Patent No. 655,691, dated August 14, 1900.

Application filed December 21, 1899. Serial No. 741,182. (No model.)

To all whom it may concern:

Be it known that I, WILLIAM CROSSLEY, a citizen of the United States, residing at New Haven, in the town and county of New Haven 5 and State of Connecticut, have invented certain new and useful Improvements in Factory-Cars, of which the following is a specification.

My invention relates to an improved factory-car or rail-truck for moving merchandise in workshops and storehouses, and particularly for use in factories for the production of rubber goods that in the processes of production require to be transported from room 10 to room or into and out of drying kilns or ovens. As it is expedient to employ railways of quite narrow gage for shop use without at the same time correspondingly reducing the width of the trucks, the sides of such cars 15 ordinarily overhang the wheels to considerable extent. If, therefore, the axles are journaled in boxes carried on the side frames of the truck, they will require to project correspondingly beyond the wheels, with the journals on their extreme ends, which construction, though heretofore commonly employed, is very disadvantageous, as it brings the weight on the axles at points far interior to 20 their journals, subjecting them to springing, 25 breaking, and extraordinary friction.

My invention has for its object to overcome the aforesaid objections and to produce a factory-car of great strength and rigidity, simple of construction, and not subject to excessive wear of journals.

To this end the improvement consists in the novel combination, with the frame, of the diagonal braces supporting the axle-boxes interior to the side sills and in the arrangement 40 and construction of parts, as hereinafter more particularly described and claimed.

In the accompanying drawings, forming a part of this specification, Figure 1 is a vertical cross-section of my improved factory-car viewed from the front, the section being 45 taken on the line xx of Fig. 2. Fig. 2 is a plan view of the frame of the truck, with the uprights in horizontal section on the line xx , Fig. 3. Fig. 3 is a side elevation of the truck. 50 Fig. 4 is an end view of an axle-box and axle

and portion of its supporting-frame. Fig. 5 is a central longitudinal section of the same. Fig. 6 shows a portion of a rack, and Fig. 7 is a plan view of a part of a stay-rod. Figs. 8, 9, and 10 are respectively front, end, and 55 lower plan views of a modified form of rack.

Referring to the drawings, A and A' designate, respectively, the end and side sills of my improved car and which comprise beams of angle-iron riveted together at the ends to 60 form a rectangular frame. The beams are arranged with the angles thereof at the upper and outer sides of the frame, presenting the flanges a^3 on the upper side of the frame and similar flanges a^4 on the outside thereof. 65 The horizontal flanges a^2 of the side sills are received under those of the ends a^3 and securely riveted thereto, as indicated by the rivet-points i in the drawings.

Across the corners of the frame are arranged 70 the diagonal stay-beams B, preferably I-shaped in cross-section and having their ends received under the upper flanges of the angle-beams and riveted thereto, as indicated by the rivet-points e , shims 10 being laid between 75 the stays and flanges of the end angle-beams to compensate for the difference of the plane of the said flanges and that of the flanges of the side beams. Said I-beams B serve as 80 braces to give the frame rigidity and also form supports for the boxes D of the axles F. Cross-stays g are extended from the diagonal stay-beams B to the side sills A' in the plane of the axle, comprising flat bars riveted to the lower flanges h of the I-beams and to suitable angle- 85 plates k , which are riveted to the flanges a^4 of the side sills, as shown in Figs. 1 and 5. The rivets m , securing the cross-stays to the I-beams, also pass through the flanges d' of the boxes D, while other rivets n pass through the 90 flanges d' and the cross-stays g , as shown in Figs. 1, 4, and 5. The boxes are thus securely fastened to rigid and unyielding framework, calculated to sustain the most severe strain 95 of the wheels.

The boxes D have cylindrical chambers 41, adapted to receive the journals R of the axles F, surrounded by the antifriction-rolls r' , freely fitting in said chamber. Said rolls are retained in place by a cap t , bolted to the 100

cross-stays at the outer ends of the boxes, and by the washers t' on the journal at the opposite ends between the boxes and wheels J . The wheels may be shrunk or forced onto the 5 axle or held in any suitable manner.

The portion of the car thus far described is adapted for various trucks and use in various situations. When intended for use in rubber manufactories, it may be provided 10 with suitable racks for hanging articles upon preparatory for transportation to the drying-kilns. To this end uprights u , of angle-iron, are riveted to the side sills A' , which support the horizontal racks u' , also of angle-iron, bolted thereto by bolts 7, passing through holes 8 in the racks and perforations 9 in the uprights, placed along the entire length thereof to permit adjustment of the racks. Stay-rods 15 5, riveted diagonally across the uprights from one to another and crossing at the center 3, as shown in Fig. 3, brace the uprights against longitudinal strains, and horizontal stays 4 connect the uprights from side to side of the car, as shown in Fig. 1. The diagonal stay- 20 rods are riveted to the lateral flanges of the upright, as shown in Fig. 7, and are twisted a quarter-turn at the points of crossing 3, as shown in detail in said Fig. 7. The racks U' are provided with the loops or wire staples 6, 25 riveted therein and adapted to receive the ends of the "sticks" or cross-bars adapted to support the lasts upon which rubber boots and shoes are formed. I have devised an improved form of rack comprising a bar of angle-iron 62, having the inclined supports or angle-pieces 63 riveted to the horizontal flange 64 thereof, as shown in Figs. 8, 9, and 10.

This improved car construction secures the utmost strength and rigidity, and in operation the springing and deflection of the axles and the friction of their journals are reduced to a minimum.

I claim as my invention and desire to secure by Letters Patent—

- 45 1. In car construction, the combination of a rectangular truck-frame, and diagonal stays connecting the sills of the truck across the corners thereof adapted to support the boxes of the axles, substantially as and for the purpose specified.
2. In car construction, the combination of a truck-frame composed of longitudinal and transverse sills connected at the ends, and diagonal stays arranged across the corners of 50 the truck-frame with their ends connected respectively to the longitudinal and trans-

verse sills, substantially as and for the purpose specified.

3. In car construction the combination of a rectangular frame composed of longitudinal 60 and transverse beams of angle-iron riveted together at their ends or corners of the truck, diagonal stay-beams arranged across the corners of the rectangle with their ends secured respectively to the longitudinal and trans- 65 verse angle-beams, and axle-boxes secured to and supported by the said diagonal stays substantially in the manner and for the purpose specified.

4. In car construction the combination of 70 the rectangular frame of side and end sill angle-beams connected at their ends, diagonal stay-beams extended across from the longitudinal to the transverse angle-beam and riveted thereto, cross stay-bars connecting 75 the side sills and adjacent diagonal stays, axle-boxes secured to the diagonal stays, and the axles journaled in said boxes and provided with truck-wheels, substantially in the manner and for the purpose specified. 80

5. In car construction the combination of the end and side sills $A A'$ of angle-iron connected at the ends, the diagonal I-beams forming stays between the sides and ends and adapted to support the axles, the cross-stays 85 joining said diagonal stays with the adjacent side sills, the boxes depending from the diagonal stays and the axles journaled therein and provided with truck-wheels, all arranged substantially in the manner and for the pur- 90 pose specified.

6. In a factory-car the combination of the end and side sills $A A'$ of angle-iron connected at the ends the diagonal beams crossing from the side to the ends and adapted to form supports for the axle-bearings, the axle-bearings attached thereto, the axle journaled in said boxes and provided with truck-wheels, the uprights riveted to the side sills and stayed together, and the racks supported by the uprights, substantially in the manner and for the purpose specified. 95

7. In a factory-car the rack comprising in combination a bar of angle-iron and the inclined supports or angle-pieces 63 riveted to the horizontal flange thereof, substantially as and for the purpose specified. 100

WILLIAM CROSSLEY.
